(57) **CLAIM**

The ornamental design for wiper for automobiles, as shown and described.

DESCRIPTION

FIG. 1 is a perspective view of wiper for automobiles showing my new design.

FIG. 2 is a front view of my design.

FIG. 3 is a left side view of my design.

FIG. 4 is a right side view of my design.

FIG. 5 is a top plan view of my design.

FIG. 6 is a bottom plan view of my design.

FIG. 7 is an enlarged fragmentary view of the encircled portion labeled as "7" in FIG. 1.

FIG. 8 is an enlarged fragmentary view of the encircled portion labeled as "8" in FIG. 2; and,

FIG. 9 is an enlarged fragmentary view of the encircled portion labeled as "9" in FIG. 5.
